UNITED STATES PATENT OFFICE.

ANTON H. NARROW, OF MEMPHIS, TENNESSEE.

TYPE BAR OR SLUG.

Application filed December 2, 1921. Serial No. 519,441.

To all whom it may concern:

Be it known that I, ANTON H. NARROW, a citizen of the United States, residing at Memphis, in the county of Shelby and State 5 of Tennessee, have invented certain new and useful Improvements in Type Bars or Slugs, of which the following is a specification.

My said invention relates to an improved type bar such as may be formed by the machine shown in my co-pending application 10 No. 519,440, of even date herewith.

It is an object of my invention to provide a type bar with means to indicate the point at which the same should be cut off.

15 Referring to the accompanying drawings which are made a part hereof and on which similar reference characters indicate similar parts,

Figure 1 is a perspective of my invention, 20 and

Figure 2 is a side elevation thereof.

In the drawings 10 indicates a type bar of conventional length bearing printing characters 11 of any usual form and to any degree 25 sired extent as is customary in the art. This type bar also carries a projection 12 which as here shown is of substantially equal height with said characters, although it could be higher than the letters or even of 30 less height and still perform its functions. This projection is spaced from the end letter S at such a distance that when the projection is held against a straight edge properly located on a sawing machine of ordinary 35 design the saw will cut through between the projection and said adjacent letter at such a distance as to space the letter to the desired extent from the left margin of the column. This as will be understood may be 40 the ordinary small space of a point or two but for display advertising it may be several inches and the projection must be spaced to a corresponding extent from the letter nearest thereto which may be done by inserting a sufficient number of blank members 45 between the jaws of a linotype machine all as explained in my above mentioned co-pending application.

As is well known it is customary to cast 50 type bars of a certain maximum length regardless of the ultimate length of the line of type which is to be set up in the form. After the bar has been cast it is measured from the right hand end and cut off to the 55 desired length. This is done by means of a sawing machine having an adjustable gauge

and the gauge must be changed every time the length of the line changes so that in the case of display type the gauge must be manipulated very frequently which causes a 60 great waste of time. By the use of my device all that is necessary is to provide a straight edge at the other side of the saw from the usual gauge, the ultimate length of the type bars being measured in effect 65 from the left end of the bar or the right hand end of the line, contrary to the present practice. As many type bars as can conveniently be handled at one operation are then placed on the saw table and pushed toward the straight edge so that the measure finding projections abut against the straight edge after which the saw is operated to cut all the type bars between the type and said projection. All the bars are thus cut off at 70 the right length on the left end, thereby doing away with any necessity of filling in with quads at the left end of a line if the print is intended to begin at a distance 75 therefrom.

Having thus fully described my said invention, what I claim as new and desire to secure by Letters Patent, is:

1. A display type bar having a part to be cut off, and an upward projection spaced 85 from the lettering on the bar and of substantially equal height therewith, said projection indicating the point of severance of the bar, substantially as set forth.

2. A display type bar having a part projecting to the left of the printing surface and means thereon indicating the position of the ultimate left-hand margin, substantially as set forth.

3. A display type bar having a portion 95 to be cut off projecting beyond the printing surface and means on the bar to indicate the length to be cut off, substantially as set forth.

4. A type bar having a portion to be cut 100 off projecting to the left of the printing surface and means on the bar to indicate the length to be severed, substantially as set forth.

5. A type bar of conventional length having a portion projecting beyond the printing surface and adapted to be cut off, and means to indicate the point of severance, substantially as set forth.

6. A display type bar having beyond the 110 printing surface a part to be cut off and provided immediately beyond said point

with an upward projection, substantially as set forth.

7. A display type bar having beyond the printing surface a part to be cut off and 5 provided immediately beyond said point with an upward projection of greater height than said printing surface, substantially as set forth.

In witness whereof, I have hereunto set my hand and seal at Memphis, Tennessee, 10 this 23rd day of November, A. D. nineteen hundred and twenty-one.

ANTON H. NARROW. [L. s.]

Witnesses:

JOHN W. FARLEY,
F. M. BAILEY.
